UNITED STATES PATENT OFFICE.

WILLIAM HENRY SIMMONS, OF NEW YORK, N. Y.

DESIGN FOR A THREAD-HOLDER AND PINCUSHION.

No. 39,515.

Specification for Design.

Patented Sept. 8, 1908.

Application filed June 23, 1908. Serial No. 440,032. Term of patent 7 years.

To all whom it may concern:

Be it known that I, WILLIAM HENRY SIMMONS, a citizen of the United States, residing at New York, in the county and State of New York, have invented a new, original, and ornamental Design for Thread-Holders and Pincushions, of which the following is a specification, reference being had to the accompanying drawing, forming part thereof.

The figure is a perspective view, showing my new design.

I claim:

The ornamental design for a thread holder and pincushion, as shown.

WILLIAM HENRY SIMMONS.

Witnesses:

ALFRED RUSSELL,
HENRY F. HILKER.
